WATER HEATING AND MEASURING APPARATUS.

1,077,350.

Specification of Letters Patent.

Patented Nov. 4, 1913.

Application filed January 31, 1912. Serial No. 674,604.

To all whom it may concern:

Be it known that I, EDWARD G. JAY, Jr., a citizen of the United States of America, residing in the city and county of Philadelphia and State of Pennsylvania, have invented a certain new and useful Improvement in Water Heating and Measuring Apparatus, of which the following is a true and exact description, reference being had 10 to the accompanying drawings, which form a part thereof.

My present invention relates to combined water heating and measuring apparatus, and particularly to apparatus for this purpose of the kind disclosed and claimed in 15 the application of George H. Gibson, Serial No. 605,879, filed February 1, 1911, in which the water is heated by the direct action of steam and the water thus heated and the 20 admixed water of condensation of the steam heating it is passed to a weir chamber divided into inlet and outlet compartments by a weir over which the water flows, provision being made for equalizing the steam pressure 25 in the weir chamber and heating chamber proper and for measuring the varying accumulation of water on the supply side of the weir to thereby maintain the rate of flow over the weir.

30 The object of the present invention is to provide improved apparatus of the kind described, characterized by the simple and effective manner in which the various parts are constructed and relatively arranged to 35 provide a compact self-contained combined heating and measuring apparatus which will be efficient and reliable in operation and may be constructed and installed with comparative cheapness and ease.

40 The various features of novelty which characterize my invention are pointed out with particularity in the claims annexed to and forming a part of this specification. For a better understanding of the invention, however, and the advantages possessed 45 by it, reference should be had to the accompanying drawings and descriptive matter in which I have illustrated and described two forms in which my invention may be embodied.

50 Of the drawings, Figure 1 is a sectional elevation of a combined water heating and measuring apparatus constructed in accord-

ance with the present invention, and Fig. 2 is a partial elevation taken similarly to Fig. 55 1 showing a modified construction.

In the drawings, A, represents a tank structure shaped to provide a horizontally elongated weir chamber divided into an inlet compartment A' and an outlet compartment A² by a weir B, which, as shown, is notched at B' to provide a discharge orifice. The tank structure is also shaped to provide a heating chamber A³ located above the weir chamber at one end of the latter. 65 The cold water to be heated is admitted to the top of the chamber A³ through the water supply pipe C. The water discharges from the pipe C into a trough D located within the heating chamber, and flows from the 70 trough D onto the trays or baffles E, as in the open feed water heaters as usually constructed.

F, represents the supply pipe for the steam for heating the water and G represents an auxiliary water supply connection to the heating chamber such as is commonly employed in connection with open feed water heaters for returning water of condensation from steam piping, radiators 80 and the like. The heating chamber, as shown in Fig. 1, is provided with a hopper-like bottom member H having at its center a discharge port to which is connected one end of the conduit I through 85 which the water falling to the bottom of the heating chamber passes to the inlet compartment A' of the weir chamber. As shown, the discharge end of the pipe I is connected to and supported by a baffle J 90 which is mounted within the inlet compartment of the weir chamber and forms a means for insuring a quiet flow and the avoidance of eddy currents in the water passing over the weir. The weir chamber 95 is connected at its top to the vapor space of the heating chamber A³ by the conduit R. The supply of water to the heating chamber through the pipe C is controlled by a valve C' connected to a float K responsive to the 100 variations in the height of water level in the outlet compartment of the weir chamber, the arrangement being such that the valve C' is cut off on a predetermined rise in the water level in compartment A² while the 105 valve is opened on a fall in this water level.

L represents an overflow channel to which surplus water passes to a float chamber M and from thence escapes through a waste pipe N and valve N', the latter being operated by a float, not shown, located in the float chamber M, which with the coöperating parts referred to, may be of the usual form commonly used in connection with open feed water heaters.

10 The float O for measuring the varying height of water level on the inlet side of the weir is located within the float chamber P in the form of a cylinder closed at its lower end, and as shown in Fig. 1, resting 15 on the bottom wall of the weir chamber on the inlet side of the weir. A pipe P' below the lowermost level having a perforated nozzle P² at its outer end passes water into and out of the float chamber as required in order 20 to equalize the water level in the latter with the water level in the compartment A' proper.

P³ represents a valve in the pipe P' by which the flow through the latter may be 25 regulated or cut off as desired.

The float chamber P need not extend to the top of the weir chamber but when it does ports P⁴ may be formed therein as shown on the drawings to equalize the vapor pressures 30 in the float chamber and the weir chamber proper. The stem O' of the float passes through the top wall of the weir chamber and operates suitable indicating, recording or registering mechanism located within a 35 casing Q which is mounted on the top of the weir chamber at the side of the heating chamber. As shown the casing Q is mounted on a base member Q' which forms a cover closing the opening formed in the top wall 40 of the weir chamber above the float chamber P. As shown, spaces Q² are interposed between the bottom of the casing Q and the base member Q' proper. Suitable stuffing box provisions or the like are made to prevent 45 leakage of steam along the float stem O' without exerting an appreciable frictional resistance to the movement of the stem. The mechanism located within the casing Q may be of the usual kind employed 50 for the purpose, examples of which are shown for instance by the Lea Patent 315,102 and by the Gibson application referred to above.

With the apparatus disclosed, as ordinarily used, the vapor pressure within the heating and weir chambers is commonly a pound or so above that of the atmosphere though it may vary from below atmospheric pressure up to ten pounds or twenty pounds 60 above atmospheric pressure. The operation of the apparatus disclosed is independent of this pressure except for its unbalanced action on the float stem O'. Owing to the relatively small cross-section of the latter this 65 unbalanced action is in general insignificant,

thus making compensating provisions unnecessary.

In the arrangement shown in Fig. 1 the heating chamber A³ is located above the outlet compartment A² of the weir chamber. A somewhat more convenient and preferable construction is illustrated in Fig. 2 which differs from the arrangement shown in Fig. 1 in that the heating chamber is located above the inlet compartment A' of the weir chamber and the heated water passes from the heating chamber A³ directly into the inlet compartment A' of the weir chamber. The bottom member H of Fig. 1 is, in effect, replaced in Fig. 2 by a portion of the top wall proper of the weir chamber, and the pipe I is entirely dispensed with in Fig. 2. In this construction the float chamber P is located in the outlet compartment A² of the weir chamber and the pipe PA, corresponding to the pipe P' of Fig. 1 is extended through the weir, the nozzle P² and the valve P³ being located, as shown, within the compartment A'.

It is apparent that apparatus constructed and arranged as described is compact and self-contained and that the arrangement of the casing Q on top of the weir chamber is a convenient one and places this mechanism in an accessible position. The compactness of the structure diminishes heat radiation losses, and the general arrangement of the apparatus facilitates its construction and installation and makes it readily possible to provide the weir compartment A' and A² with the necessary storage capacity and horizontal cross sectional area. The storage capacity and horizontal cross sectional area of the inlet compartment A' makes it possible to correspondingly diminish or entirely do away with the storage reservoir space ordinarily provided in the heating chamber proper while at the same time keeping the apparatus in a compact and convenient form.

To appreciate the extent to which the features of construction disclosed coöperate in making possible a highly compact and convenient structure it is necessary to understand that the conditions of operation prescribe certain minimum limits on the capacity and horizontal cross sectional areas of both the weir chamber compartments A' and A². The inlet compartment A' must have sufficient depth and horizontal area to insure a fairly quiet flow over the weir at the times at which the maximum inflow of water into the weir chamber occurs and when this inflow is most irregular. The outlet compartment must have sufficient storage capacity to accommodate all the water which may accumulate on the supply side of the weir above the lowermost level of flow over the weir without interfering with the free flow over the weir in order to avoid

such interference when, as may sometimes occur, the withdrawal of water from the weir chamber suddenly ceases after a period in which the flow of water into the weir chamber has been at a maximum. Furthermore, the horizontal cross sectional area of the outlet compartment A² should be great enough so that ordinary changes in the rate at which water is withdrawn from the weir 5 chamber will make comparatively small changes in the height of water level in the outlet chamber; for, if such changes in the height of water level are too great it is difficult to arrange the valve C' and its float actuating mechanism so that the valve will not close too much or open too widely on moderate changes in the rate at which water is withdrawn from the weir chamber. The effect of too great an opening or closing movement of the valve C' under these conditions is to produce unnecessary and undesirable fluctuations in the rate at which cold water is passed into the heating chamber and weir 10 chamber. In consequence of these considerations it is necessary that the horizontal cross sectional area of the outlet compartment A' at the level of the water therein must be approximately equal to or greater, and never substantially less than the corresponding area of the inlet compartment, and ordinarily, in the type of apparatus disclosed, the weir is advantageously arranged approximately midway between the ends of the weir chamber.

35 The heating chamber A³ must discharge into, and the float tank P must be connected with the inlet compartment A' of the weir chamber; but where the apparatus is made as compact as the conditions of operation permit, it is not possible to locate both the heating chamber and the mechanism actuated by the valve above the inlet compartment of the weir chamber. This difficulty is avoided with my arrangements by locating the heating chamber A³ above the weir chamber at one end of the latter, and by locating the float tank P in the weir compartment at the other end of the weir chamber from that at which the heating chamber 40 is located, and by connecting either the heating chamber as shown in Fig. 1, or the float chamber as shown in Fig. 2 to the inlet compartment A' by a conduit passing over or through the weir.

45 While in accordance with the provisions of the statutes I have illustrated and described the best forms of my invention now known to me it will be apparent to those skilled in the art that changes may be made 50 in the form of the apparatus disclosed with-

out departing from the spirit of my invention, and that under some conditions certain features of my invention may be used with advantage without a corresponding use of other features.

65

Having now described my invention what I claim as new and desire to secure by Letters Patent is:

1. Water heating and measuring apparatus comprising in combination a weir chamber, a weir located in said weir chamber approximately midway between the ends of the latter and dividing said chamber into inlet and outlet compartments, a heating chamber above the weir chamber at one end 70 of the latter, steam and water supply connections to said heating chamber, provisions for conveying the water heated therein to the inlet compartment of the weir chamber, a float chamber located within the compartment of the weir chamber at the opposite end of the latter from said heating chamber and provisions placing said float chamber in communication with said inlet compartment below the lowermost level of flow over 75 the weir, a float located within the float chamber and having a stem projecting through the top wall of the weir chamber, and coöperating float actuated mechanism mounted on top of the weir chamber above 80 said float chamber.

2. Water heating and measuring apparatus having in combination, a unitary tank structure comprising a weir chamber and a heating chamber above the weir chamber at 95 one end of the latter, a weir dividing said weir chamber into inlet and outlet compartments, said inlet compartment being at the end of the weir beneath said heating chamber, steam and water supply connections to 100 said heating chamber, provisions for conveying the water heated therein to the inlet compartment of the weir chamber, a float chamber located within the outlet compartment of the weir chamber, a conduit connecting said float chamber to said inlet compartment below the lowermost level of flow over the weir, said float chamber being also 105 open to the weir chamber above the maximum height of water level therein, a float 110 located within the float chamber and having a stem projecting through the top wall of the weir chamber, and coöperating float actuated mechanism mounted on top of the weir compartment above said float chamber. 115
